UNITED STATES PATENT OFFICE.

GUSTAV MANTHEI, OF WISMAR, GERMANY.

SCISSORS WITH MOVABLE PIVOT.

1,072,136.

Specification of Letters Patent.

Patented Sept. 2, 1913.

Application filed June 27, 1910, Serial No. 569,160. Renewed May 31, 1913. Serial No. 771,114.

To all whom it may concern:

Be it known that I, GUSTAV MANTHEI, a subject of the King of Prussia, and resident of Wismar, Germany, have invented certain new and useful Improvements in Scissors with Movable Pivots, of which the following is a specification.

This invention relates to scissors, and more particularly to scissors for tailors.

With the scissors of known construction it is much easier to cut the cloth when the scissors are wide open than when the same are opened only very little so that the front ends of the scissors cut the cloth. Therefore it follows that much more force is required to cut with the points of the scissors than with their inner cutting edges, or better expressed with the rear parts of the cutting edges. The reason is that the leverage of the scissors remains always the same and does not adjust itself automatically according to the degree of opening of the scissors. This inconvenience is overcome by the present invention according to which the pivot of the scissors blades is movable and arranged in such a manner that it adjusts itself according to the degree of opening of the blades.

In the accompanying drawings the improved scissors are shown by way of example.

Figure 1 shows the scissors open and Fig. 2 represents the same closed.

The members *a*, *b* of the improved scissors are movably mounted upon the pivot *c*. The handles of the scissors have each an extension at the outer end upon which the pivots *d*, *e* respectively are fixed. Upon said pivots *d*, *e* the ends of curved levers *f* are pivotally mounted, whose other ends are pivotally fixed upon the common pivot *g* which is

fixed upon the outer end of a pushing rod *h* whose other end carries the pivot *c* of the members *a*, *b*. This pivot *c* is located in longitudinal slots *i* of the scissors members *a*, *b* in which it can slide.

When the scissors are being opened, the members *a*, *b* open at the front end in turning around the pivot *c*, which however is pulled toward the handle as the pivots *d*, *e* which move laterally with the handles pull the rod *h*, so that the pivot *c* is moved in the slot *i*, its position varying according to the degree of opening of the scissors blades. Therefore it follows that the leverage varies with the degree of opening, that is to say the lever arm becomes longer the more the scissors are closed and becomes shorter the more the same are opened.

I claim:

Improved scissors comprising in combination with the blades having longitudinal slots at the center of motion, extensions at the outer end of each handle, pivots upon said extensions, curved levers pivoted at the one end to said pivots, a pushing rod, a pivot at the outer end of said pushing rod upon which the inner ends of said curved levers are pivoted and a pivot at the other end of said pushing rod located in the longitudinal slots of the blades and forming the center of motion for the same so that this center of motion adjusts itself according to the degree of opening of the scissors, substantially as described and shown and for the purpose set forth.

In witness whereof I have hereunto set my hand in the presence of two witnesses.

GUSTAV MANTHEI.
